UNITED STATES PATENT OFFICE.

WALTER S. ADAMS, OF PHILADELPHIA, PENNSYLVANIA, ASSIGNOR TO THE J. G. BRILL CO., OF PHILADELPHIA, PENNSYLVANIA, A CORPORATION OF PENNSYLVANIA.

DESIGN FOR A CAR-TRUCK BOLSTER.

45,682.

Specification for Design.

Patented Apr. 28, 1914.

Application filed February 11, 1914. Serial No. 818,167. Term of patent 14 years.

To all whom it may concern:

Be it known that I, WALTER S. ADAMS, a citizen of the United States, residing at Philadelphia, in the county of Philadelphia and State of Pennsylvania, have invented a new, original, and ornamental Design for Car-Truck Bolsters, of which the following is a specification, reference being had to the accompanying drawing, forming part thereof, in which—

Figure 1 is a plan view of a car truck bolster, showing my new design; Fig. 2 is a side elevation of the same; Fig. 3 is a

plan view of the bolster, looking at the underside; Fig. 4 is an end elevation of the bolster; and Fig. 5 is a sectional view on the line 5—5 of Fig. 2, looking in the direction of the arrows.

I claim:

The ornamental design for a car truck bolster as shown.
